UNITED STATES PATENT OFFICE.

GEORGE W. HAMILTON, OF GLOBE, ARIZONA TERRITORY.

CAR-COUPING.

SPECIFICATION forming part of Letters Patent No. 623,542, dated April 25, 1899.

Application filed June 5, 1897. Renewed November 3, 1898. Serial No. 695,416. (No model.)

To all whom it may concern:

Be it known that I, GEORGE W. HAMILTON, a citizen of the United States, residing at Globe, in the county of Gila and Territory of 5 Arizona, have invented a new and useful Car-Coupling, of which the following is a specification.

This invention relates to improvements in car-couplings.

10 The object of the invention is to improve the construction of car-couplings and to provide a device of this character which shall be automatic in operation, thereby overcoming the necessity of an attendant passing between 15 cars to couple or uncouple the same; and, further, the invention contemplates a coupling which shall be so constructed as to support a link in its proper position for readily entering an opposing draw-head when coupling 20 and which shall also prevent dirt and other foreign substances accumulating in the draw-head.

With these objects in view the invention consists, substantially, in the construction, 25 combination, and arrangement of parts, as will be hereinafter fully illustrated, described, and claimed.

In the accompanying drawings, Figure 1 is a perspective view of a car-coupling constructed in accordance with the present invention. Fig. 2 is a longitudinal sectional view thereof. Fig. 3 is a sectional plan view, the pin-supporting block being removed. Fig. 35 Fig. 4 is a transverse sectional view on the line 4-4, Fig. 3. Fig. 5 is a detail perspective view of the pin-supporting block.

Similar numerals of reference indicate corresponding parts throughout the figures.

Referring to the drawings, 1 designates a 40 draw-head, which may be formed of any suitable material adapted for the purpose and gradually tapers from one end to the other, as clearly shown, a coupling-pin 2 being arranged at the enlarged end of said draw-head 45 and passing through vertically-alined openings 3, formed in said end.

Disposed within the draw-head 1 is a sliding pin-supporting block 4, which block may be of any desired material, and formed centrally at the inner end of said block and extending therefrom is a stem 5, which is adapted to slide within a central longitudinal pas-

sage 6, extending from the inner end wall of the draw-head and through the latter toward its rear end. Encircling the stem 5 is a coiled 55 spring 7, which exerts its tension to force the pin-supporting block 4 outwardly, and formed in said stem 5 is an elongated slot 8, through which passes a securing-pin 9, said pin extending through the draw-head 1, and thereby limits the outward movement of the pin-supporting block 4. It is to be noted that the coiled spring 7 lies between the inner end of the pin-supporting block 4 and the securing-pin 9, so that when said pin-supporting block 60 is forced inwardly said coiled spring is compressed, the elongated slot 8 permitting said block being capable of an inward sliding motion, and by reason of the compression of said coiled spring 7 the pin-supporting block 4 will 65 be immediately forced outwardly when pressure thereon is removed.

The outer end of the pin-supporting block 4 is inclined, and formed at the center of said inclined end is a nose 10, which nose divides 75 said inclined end into a pair of notches 11, the object of the nose 10 being to properly support a link when the latter has been placed in the draw-head, and thereby hold said link in a position for readily entering an opposing 80 draw-head when coupling, the link for use with the herein-described coupling being slightly modified from the ordinary construction by providing at each of its ends a central notch which is adapted to receive the nose 85 10, and by reason of said nose entering the notch in the end of the link said link is supported in its proper position. While only a pair of notches 11 have been illustrated as formed in the outer end of the pin-supporting 90 block 4, it will of course be understood that as many as desired may be employed, the ends of the link being correspondingly notched, so as to register with and be held by the pin-supporting block when said link has been inserted in the draw-head.

Mounted upon the end of the draw-head 1, in which the coupling-pin 2 is disposed, is a transversely-arranged guide-plate 12, through which said coupling-pin passes, and said 100 guide-plate is secured upon the draw-head 1 by pins 13, which pass through the ends of said guide-plate and enter and project through the upper flanged edges of said draw-head,

and for securely holding said pins staples 14 or their equivalent are employed. The staples 14 are removably secured in the ends of the pins 13 and will thereby permit the guide-
 5 plate 12 being easily detached from the draw-head 1 should the coupling-pin 2 be injured in any manner as to prevent it properly performing its functions. At the upper end of the coupling-pin 2 a head-plate 15 is attached,
 10 said plate resting upon a shoulder 16, formed by reducing the upper end of the coupling-pin, and the plate 15 is secured to the coupling-pin by a key or ring 17. The key or ring consists of a piece of metal passed through
 15 the perforation of the coupling-pin at a point above the shoulder 16 and having its end bent, as shown, while the metal is cold, so that the key or ring may be readily opened and disengaged from the coupling-pin to per-
 20 mit the latter to be removed should it become bent, broken, or otherwise injured. The head-plate 15 is provided at its ends with openings 18, and is connected with the guide-plate 12 by stay-chains 19, which are linked
 25 into suitable eyes 20 of the guide-plate. The stay-chains 19 limit the upward movement of the coupling-pin and prevent the same from accidentally leaving the guide-plate, and the plate 15 prevents the stay-chains from twist-
 30 ing around the coupling-pins, as would be the case were the stay-chains attached directly to the coupling-pin instead of to the head-plate. By this construction the coupling-pin is limited in its vertical movement to prevent
 35 it from leaving the coupling-pin perforation of the draw-head, and it may be readily applied to any ordinary draw-head. The connection between the coupling-pin and the draw-head also permits the former to be read-
 40 ily removed should it become broken.

The floor of the draw-head 1 is provided with a series of longitudinal grooves 21, at the inner end of each of which an escape-opening 22 is formed, said openings being provided
 45 in the floor of the draw-head, and any dirt or other foreign substances which may enter said draw-head pass into the longitudinal grooves 21 and through the escape-openings 22, thereby preventing undue accumulation
 50 of such substances within said draw-head. The grooves 21 extend the entire length of the opening which receives the pin-supporting block, so that the entire surface over which the block moves is grooved, and any
 55 accumulation will be carried along the groove by the block to the escape-openings or to the outer end of the floor of the draw-head. In rear of the escape-openings 22 and formed at the bottom of the central longitudinal pass-
 60 sage 6 is an elongated slot 23, the purpose of which is to permit the insertion of a suitable implement for holding the inner end of the coiled spring 7 until the securing-pin 9 may be passed through the slot 8, formed in the
 65 stem 5 of the pin-supporting block 4.

In the upper side of the draw-head 1 and at the rear end of the latter, a circular socket

24 is formed, at one side of which is a guide-slot 25, and disposed in the socket 24 is the pear-shaped head 26 of a coupling-bar 27, 70 said coupling-bar lying within the slot 25 and being held therein by a transverse pin 28. Through the medium of the coupling-bar 27 and the manner in which the same is connected to the draw-head 1 it will be readily seen 75 that said draw-head may be secured to a car in a very simple but durable manner.

For the purpose of elevating the coupling-pin 2 a chain 29 is secured to the coupling-pin by means of the key or ring 17, and the upper end of the chain is designed to be connected with any suitable operating mechanism for enabling the coupling-pin to be elevated from the top and sides of a freight-car or the platform of a coach. 85

The operation and advantages of the herein-described car-coupling will be readily understood by those skilled in the art. When it is desired to use the coupling, a link similar to that shown in the drawings is inserted in the draw-head 1 by first elevating the coupling-pin 2 and then forcing the sliding pin-supporting block 4 into said draw-head. This will enable the link to be passed into a position where the coupling-pin may be dropped 95 through the same, and by reason of the coiled spring 7 exerting its tension to force the pin-supporting block outwardly the nose 10 is forced into the notch in the end of the link, thereby pressing the latter against the coupling-pin 2. From the fact that the outer end of the pin-supporting block 4 is inclined to permit the coupling of cars having draw-heads arranged at different elevations and that the notches 11 formed therein receive the 105 end of the link said link will be supported in its proper position for entering an opposing draw-head without the necessity of an attendant passing between the cars. When, however, the link is in the approaching draw- 110 head, the coupling-pin is held in a position to lock the couplings by the supporting-block 4, which is forced outwardly by the coiled spring 7 to a sufficient extent as to lie beneath the upper opening 3 in the draw-head, thus forming a support for the lower end of the pin 2, and when the link which is carried by the approaching draw-head contacts with said pin-supporting block 4 the latter is forced inwardly and slides from beneath the coupling- 115 pin, which drops by gravity through the link and couples the draw-heads. To release the coupling-pin 2, the operating-chain 29 is manipulated so as to raise said coupling-pin, when the link may be readily withdrawn, and by 120 reason of the stay-chains 19 limiting the upward movement of the coupling-pin 2 said pin may be drawn to a sufficient height as to enable the pin-supporting block 4 sliding outwardly to a sufficient extent as to retain the 130 pin in its elevated position for coupling.

From the foregoing it will be seen that I have provided a car-coupling which is simple, efficient, and durable; that the same is auto-

matic in operation, thereby overcoming the necessity of an attendant passing between cars to couple or uncouple the same; that the link is supported in its proper position for readily entering an opposing draw-head when coupling, and, finally, that dirt and other foreign substances are prevented accumulating in the draw-head, thus permitting the coupling to always remain clean and in a condition

10 for easy operation.

Having thus described the invention, what is claimed as new, and desired to be secured by Letters Patent, is—

1. A car-coupling comprising a sliding pin-15 supporting block, a draw-head having a coupling-pin perforation and provided with an opening to receive the pin-supporting block and having in its floor, a series of longitudinal grooves arranged at intervals in the spaces 20 between the coupling-pin perforation and the sides of the draw-head and extending inward from the front thereof the entire length of the block-receiving opening and provided near their rear ends with escape-openings extending through the floor of the draw-head, said grooves being adapted to carry off dirt and other foreign matter and prevent the same from clogging the sliding block, and a coupling-pin arranged in the coupling-pin 25 perforation and adapted to be supported by the block, substantially as described.

2. In a car-coupling, the combination of a draw-head, a coupling-pin, a sliding pin-supporting block mounted within the draw-head 35 and having its outer end inclined and provided with a centrally-arranged nose extending upward from the lower face of the block to the top thereof, and a link provided at each of its ends with a central notch adapted to be 40 engaged by the nose of the block whereby the link is interlocked with the block and held against lateral or downward movement to maintain it in position for guiding it into the mouth of another draw-head, substantially as 45 described.

3. In a car-coupling, the combination of a draw-head provided with a coupling-pin perforation, the transverse guide-plate 12 arranged on the top of the draw-head and provided with a perforation registering with the coupling-pin perforation, a transverse head-plate 15 having a perforation, the coupling-pin arranged in the perforations of the draw-head and the plate 12 and having its upper 55 end reduced and passing through the perforation of the head-plate 15, an operating-chain engaging the upper end of the coup-

ling-pin and securing the same to the head-plate, the stay-chains 19 connecting the ends of said plates to limit the upward movement 60 of the coupling-pin, and the vertical fastening devices passing through the ends of the guide-plate 12 and through the upper portion of the draw-head and detachably mounting the guide-plate thereon, substantially as de- 65 scribed.

4. A car-coupling, comprising a draw-head having its shank constructed of a single piece of metal and provided with a socket having a guide-slot at one of its sides, a headed coupling-bar disposed in said socket and guide-slot and adapted to secure the draw-head to a car, and a transverse fastening device for retaining said coupling-bar in said socket and guide-slot, substantially as set forth. 75

5. A car-coupling, comprising a draw-head provided in its floor with a series of longitudinal grooves having escape-openings through said floor to prevent accumulation of dirt and other foreign substances within said draw-head, said draw-head being also provided with a longitudinal passage, a pin-supporting block disposed within the draw-head and provided with a stem having an elongated slot formed therein, said stem sliding within the 85 longitudinal passage, a coiled spring encircling said stem, a securing-pin passing through the slot of the stem and the draw-head and adapted to limit the outward movement of the pin-supporting block, said coiled 90 spring being disposed between the inner end of the pin-supporting block and said securing-pin and adapted to force said pin-supporting block outwardly, a coupling-pin disposed in the draw-head and adapted to be 95 retained in an elevated position by the supporting-block, a guide-plate mounted upon the draw-head, pins passing through said guide-plate and the draw-head and adapted to secure the guide-plate on the latter, a head-plate secured to the coupling-pin, stays connected to the ends of the head-plate and the 100 guide-plate and adapted to limit the upward movement of the coupling-pin, and means for operating the coupling-pin, substantially as 105 set forth.

In testimony that I claim the foregoing as my own I have hereto affixed my signature in the presence of two witnesses.

GEO. W. HAMILTON.
